UNITED STATES PATENT OFFICE.

MATHIAS WAGNER, OF KOKOMO, INDIANA, ASSIGNOR OF THIRTY ONE-HUNDREDTHS
TO FINIS F. HUNT.

FAN ATTACHMENT FOR ROCKING-CHAIRS.

1,210,569.

Specification of Letters Patent. Patented Jan. 2, 1917.

Application filed February 2, 1915. Serial No. 5,752.

To all whom it may concern:

Be it known that I, MATHIAS WAGNER, a citizen of the United States, residing at Kokomo, in the county of Howard and 5 State of Indiana, have invented a new and useful Fan Attachment for Rocking-Chairs, of which the following is a specification.

The present invention appertains to rocking chair fans, and aims to provide a novel 10 and improved fan attachment for rocking chairs, whereby the oscillation of the chair may be taken advantage of for rotating a cooling fan.

The present invention contemplates the 15 provision of a fan attachment for rocking chairs embodying a unique assemblage of component parts, whereby the attachment may be readily applied to a rocking chair, and will be adjustable to accommodate various 20 sizes and styles of chairs, the present attachment being adapted to be disposed at the rear of the chair so that it will not inconvenience the use of the chair in the usual manner.

25 Another object of this invention is to equip the attachment with novel means whereby the rocking motion of the chair will impart a rotary movement to the fan for cooling the occupant of the chair.

30 With the foregoing and other objects in view which will appear as the description proceeds, the invention resides in the combination and arrangement of parts and in the details of construction hereinafter described and claimed, it being understood that changes in the precise embodiment of 35 the invention herein disclosed can be made within the scope of what is claimed without departing from the spirit of the invention.

40 The invention has been illustrated in its preferred embodiment in the accompanying drawing, wherein:—

Figure 1 is a side elevation of the attachment as applied to a rocking chair. Fig. 2 45 is a rear view thereof. Fig. 3 is an enlarged sectional detail taken on the line 3—3 of Fig. 1. Fig. 4 is an enlarged sectional detail taken on the line 4—4 of Fig. 1.

50 In carrying out the present invention, there is provided a yoke 1 constituting the end strips or bars 2 which are attached at their remote ends to the rear ends of the rockers 3 of the rocking chair, by means of

U-clips or bolts 4 straddling the rear ends 55 of the rockers 3 from below and terminally engaged through the strips or bars 2. The yoke or cross member 1 also includes an intermediate strip or bar 5 overlapping the inner ends of the strips or bars 2, the overlapped portions of the strips or bars 2 and 5 being slotted, as at 6, and clamping bolts 7 being engaged through the coöperating slots 6 to clamp the strips or bars 2 and 5 at any position to which they are set. It 60 will also be obvious that the yoke 1 is extensible and contractible by loosening the clamping bolts 7, whereby the yoke 1 will accommodate various rockers 3 which are spaced apart more or less, the U-bolts or 70 clips 4 being readily applied to the ends of the rockers 3 as will be obvious.

The intermediate strip or bar 5 of the yoke 1 is provided intermediate its ends with an opening 8 and with upstanding ears 75 9 at the sides of the opening 8, and a sleeve 10 is fulcrumed between the ears 9 within the opening 8 by means of trunnion or pivot screws or elements 11 threaded or otherwise engaged through the ears 9 and pivotally 80 engaging the opposite sides of the sleeve 10. In this manner, the sleeve 10 may oscillate about a transverse axis parallel with the transversely disposed yoke 1.

A standard 12 is slidable through the 85 sleeve 10 to oscillate therewith, and carries a caster 13 at its lower end which is adapted to rest upon the floor or surface upon which the rocking chair sets. The standard 12 and opening of the sleeve 10 are preferably non- 90 circular or angular in cross section to permit the standard 12 and sleeve 10 to slide relative to one another, and to prevent the standard 12 from rotating within the sleeve 10.

95 A bracket or plate 14 is adapted to be secured in any suitable manner to the back 14^a of the rocking chair adjacent the upper end of the said back and is provided with an upper rearwardly projecting fork 15 which has 100 engaged through its arms, a pair of opposite trunnion or pivot screws 16, and a sleeve 17 is trunnioned or pivotally mounted between the inner ends of the screws or pivot elements 16. A rotary fan shaft 18 is journaled to the sleeve 17, and a pair of collars 19 are secured by means of set screws or in any other suitable manner upon the shaft 18

immediately above and below the sleeve 17, to hold the shaft 18 against sliding movement through the sleeve 17. Ball bearings 20 are disposed between the collars 19 and the sleeve 17, to enable the shaft 18 to rotate freely within the sleeve or bearing 17, the rollers 19 and sleeve 17 being provided with suitable ball races for receiving the ball bearings as will be obvious. The sleeve or bearing 17 being trunnioned within the fork 15, will enable the fan shaft 18 to oscillate backwardly and forwardly about a transverse axis, when necessary.

The yoke 1 and bracket 14 are connected by a tie or connecting rod 21 which is terminally engaged at its upper end through a web 22 connecting the arms 22 of the fork 15, and which has its lower end engaged through a forwardly projecting ear 23 provided upon the intermediate strip or member 5 of the yoke 1. Nuts 24 are threaded upon the upper and lower end portions of the tie rod 21 to seat against the web 22 and ear 23, respectively, for tightening the tie rod 21 and to brace the corresponding parts of the present device, as well as the chair structure.

The fan 25 is carried by the upper protruding end portion of the shaft 18, and embodies a hub 26 adjustably secured upon the shaft 18 in any suitable manner, and having the inner ends of the shanks 27 of the blades 28 secured thereto in any suitable manner, whereby the blades 28 may be swung to various angular positions about axes intersecting the shaft 18. The fan 25 overhangs the rocking chair, whereby when the fan is rotated it will create a current of air to the comfort of the occupant of the chair.

In order to rotate the fan shaft 18, the lower end of the fan shaft 18 is operatively connected to the upper end of the standard 12 through the medium of a power transmitting device 30 for converting a reciprocatory motion into rotary motion. The power transmitting device 30 in the present instance, utilizes what is termed in the market and trades, a "Yankee" screw driver embodying a screw 31 received by a socket 32 which contains means co-operating with the screw 31 whereby when the screw 31 and socket 32 are reciprocated relative to one another, the screw 31 is rotated. The details of the power transmitting device or mechanism 30 are old and well known, and since they form no part of the present invention, they need not be described or illustrated in detail. In the present case, the upper end of the screw 31 is attached to the lower end of the fan shaft 18, and the lower end of the socket 32 is secured to the upper end of the standard 12, whereby when the standard 12 and the shaft 18 move to and from each other, due to the rocking motion of the chair, the fan shaft 18 will be rotated with the screw 31, the device or mechanism 30 being

preferably so arranged that when the shaft 18 is depressed so as to depress the screw 31, it will cause the shaft 18 to be rotated.

In operation, after the attachment has been properly applied to a rocking chair, and when the occupant of the chair rocks the same back and forth, as usual, the rearward movement of the chair will cause the back of the chair to swing rearwardly and downwardly, thereby carrying the sleeve or bearing 17 in a similar direction, and which will depress the shaft 18 for rotating it. The oscillation of the chair will thus impart a rotary movement of the fan 25 for creating a current or draft of air to the comfort of the occupant. The standard 12 and the shaft 18, which are in alinement, may oscillate slightly relative to the chair if necessary to prevent a binding action, as the chair is rocked, since the sleeve 10 of the standard 12 is trunnioned to the yoke 1 and the sleeve or bearing 17 of the shaft 18 is trunnioned to the bracket 14. The sleeve 10 will also slide up and down upon the standard 12, as the rockers 3 move back and forth. The caster 90 enables the lower end of the standard 12 to rest upon the floor in a convenient manner, whereby the standard 12 may be moved about with the chair, without marring the floor, or tearing the carpet or rug upon which the standard may be seated. The present device therefore offers no hindrance to the convenient use of the rocking chair, but upon the other hand, the fan will increase the comfort of the occupant without material exertion upon his or her part. The rocking motion of the chair imparts a reciprocatory motion to the fan shaft 18, and the device or mechanism 30 in turn transforms the reciprocatory motion of the fan shaft 18 into a rotary motion thereof for actuating the fan in a convenient and desirable manner.

An important feature of the invention resides in the fact that the device can be attached with equal facility and success to various styles of rocking chairs. This is due to the trunnioning of the bearing 17 and sleeve 10 to the bracket 14 and the yoke 1 respectively, the trunnions being so arranged as to permit the bearing and sleeve to swing in a common vertical plane when the yoke is adjusted to the rockers of the chair. Thus, in applying the device to any rocking chair, the bracket is first attached to the back of the chair without regard to the particular position of the bracket in a vertical plane, and the yoke 1 can then be applied to the rockers at any suitable point thereof and at any suitable angle transversely with the standard 12, since the bearing 17 and sleeve 10 will swing in said plane and adjust themselves relative to the bracket and yoke to remain in alinement. Referring to Fig. 1, it will be noted that the yoke 1 can be ad-

justed along the rockers 3 without in any way impairing the operation of the device and without causing any of the working parts to bend or bind.

5 Having thus described the invention, what is claimed as new is:—

A fan attachment for rocking chairs, embodying a bracket attachable to the back of a rocking chair and having a fork, a bearing 10 trunnioned within said fork, a shaft journalized through said bearing to move vertically therewith, a fan carried by said shaft, a yoke having means for attaching it to the rear ends of the rockers of the chair, said 15 yoke having an opening between its ends, a sleeve disposed within said opening and trunnioned to the yoke, a standard slideable through the sleeve to rest upon the floor, the

standard and sleeve being of non-circular cross section to prevent the rotation of the 20 standard, and a power transmitting device connecting the shaft and standard for transforming the reciprocatory movement of the shaft into a rotatory motion thereof, the trunnions of the bearing and sleeve being so 25 arranged as to permit the bearing and sleeve to swing in a common vertical plane when the yoke is adjusted to the rockers.

In testimony that I claim the foregoing as my own, I have hereto affixed my signature 30 in the presence of two witnesses.

MAT. WAGNER.
